Primary Examiner — Cynthia Ramirez*(74) Attorney, Agent, or Firm* — KA Filing LLC; Wayne V. Harper; Cynthia Flanigan(57) CLAIM

We claim the ornamental design for a compost bin, as shown and described.

DESCRIPTION

FIG. 1 is a perspective view of a compost view showing our new design;

FIG. 2 is a Front view thereof;

FIG. 3 is a Back view thereof;

FIG. 4 is a Right-side view thereof;

FIG. 5 is a Left-side view thereof;

FIG. 6 is a Top view thereof; and,

FIG. 7 is a Bottom view thereof.

The broken lines are only for environmental purposes and form no part of the claimed design.
